INVENTOR

Frank C. Roberts

UNITED STATES PATENT OFFICE.

FRANK C. ROBERTS, OF PHILADELPHIA, PENNSYLVANIA.

HOT-BLAST STOVE.

SPECIFICATION forming part of Letters Patent No. 614,894, dated November 29, 1898.

Application filed August 9, 1898. Serial No. 688,221. (No model.)

To all whom it may concern:

Be it known that I, FRANK C. ROBERTS, a citizen of the United States, residing at Philadelphia, in the county of Philadelphia, State 5 of Pennsylvania, have invented an Improvement in Hot-Blast Stoves, of which the following, taken in connection with the accompanying drawings, is a full and clear specification.

10 My invention relates to improvements in hot-blast stoves, whereby the tendency to accumulate dirt and dust in the checker-work is decreased. I attain these objects in the manner illustrated in the accompanying drawings, in which—

Figure 1 is a vertical section through a two-pass hot-blast stove; Fig. 2, a horizontal cross-section through A B, (see Fig. 1;) Fig. 3, a horizontal section through C D, (see Fig. 1;) 20 and Fig. 4, a vertical section through the bottom of the stove, taken at right angles to Fig. 1 on line E F.

Similar letters refer to similar parts throughout the several views.

25 As ordinarily constructed a two-pass hot-blast stove of the type illustrated in the drawings is built so that the waste gas from the blast-furnace is admitted to and burned in the flue E, the products of combustion passing upward to the space F at the top of the stove, where they are drawn downward by the draft of the chimney through a series of flues H, said flues being surrounded by fire-brick walls I and J, these flues H and walls 30 I and J being known as "checker-work." In this manner the checker-work becomes highly heated. This heat is in turn imparted to the air-blast for the furnace by disconnecting the gas from the stove and allowing the air-blast 35 on its way to the furnace to pass through the highly-heated flues.

Below the flues H is usually provided a chamber in which are located the walls supporting the checker-work and to which is connected the opening leading to the chimney, thus providing connection between the chimney and all flues H at one and the same time. My improvement relates to the part of the stove immediately under the checker-work. 40 Otherwise my construction is similar to that usually employed.

The waste gases from a blast-furnace carry

a considerable quantity of dirt and dust. A large portion of this dirt and dust is deposited upon the top of the checker-work in the ordinary construction of a two-pass stove described above. This deposition of dirt is due to the large combined sectional area of the flues H and consequent low velocity of flow of the products of combustion. 55

The object of my invention is to so construct a two-pass stove that the velocity of the products of combustion where they enter the checker-work will be increased without reducing the heating capacity of the stove. To 60 this end I extend the chimney connection G into the stove until it meets the wall K. This extension of the chimney connection I prefer to construct with arch L, carried by side walls M. The checker-work is supported by 65 side walls N, placed at right angles to M and having between them spaces O, which communicate with the flues H in the checker-work. In M, I provide openings P, leading from O to the chimney connection or flue G. 70 On top of the arches L and extending under the checkers in line with one of the walls J, I provide a wall Q, the purpose and evident result of this wall being to divide the checker-work in two halves vertically. In the openings P, I provide dampers R, carried by rods or shafts S, to which they are attached, these dampers being operated from the outside of the stove by means of the crank T, attached to S. 75

The operation of my improvement is as follows: When it is desired to heat the stove, gas is admitted to and burned in flue E, the dampers R on one side only of G being open. As a result the products of combustion are 80 drawn downward through one-half only of the checker-work, a condition which doubles the velocity of flow over what it would be in case the stove were of ordinary construction. When one-half of the stove is heated, the 85 dampers on the heated side of the stove are closed and those on the cold side opened and the heating process repeated.

The flue E, I call the "up-pass," and the flues H, collectively, I call the "down-pass." 90

I do not limit my invention to the form or construction of flue G, dampers R, or the operating device for said dampers shown in the drawings. Any approved form or con-

struction may be employed, provided the application is made to a two-pass stove consisting of one up-pass and one down-pass.

Having fully described my invention, what 5 I claim, and desire to cover by Letters Patent, is—

In a two-pass hot-blast stove consisting of one up-pass and one down-pass, the combination of a system of checker-work located in the 10 down-pass, a chimney-flue extending across and under said checker-work, a wall or other device coinciding with said chimney-flue and dividing the checker-work into two halves ver-

tically, a series of openings in each side of said chimney-flue forming connections between the adjacent half of the checker-work and the chimney-flue, dampers placed in said openings and a device or devices for operating said dampers.

In testimony whereof I have hereunto set 20 my hand this 3d day of August, 1898.

FRANK C. ROBERTS.
